BOTTLE BOTTOM INSERTING AND SPINNING MECHANISM FOR PAPER BOTTLE MAKING MACHINES

Andrew Bodor, Newark, N. J., assignor to Reinforced Paper Bottle Corporation, New York, N. Y., a corporation of Delaware

Application March 9, 1933, Serial No. 660,088

7 Claims. (Cl. 93—55)

My invention relates to improvements in bottle bottom inserting and spinning mechanism for paper bottle making machines, and the object of the invention is to devise a simple mechanism for automatically successively feeding discs to the point of insertion and inserting them in the bottle bottom and then transferring the bottle body and the inserted disc to a spinning point, and then spinning the edge of the bottle body and disc, and it consists essentially of the arrangement and construction of parts as hereinafter more particularly explained.

Fig. 1 is a side elevation showing a portion of the body of a paper bottle making machine and the bottom inserting and spinning mechanism carried thereby.

Fig. 2 is an enlarged detail elevation of the bottle bottom inserting mechanism showing the parts in the position they assume as the disc blanks forming the bottle bottom are fed into the mechanism.

Fig. 3 is a similar view to Fig. 2 showing the parts in the position they assume when the bottle bottom is being inserted in the bottle body.

Fig. 4 is a plan view of the parts shown in Figs. 2 and 3.

Fig. 5 is a side elevation of the mechanism shown in Figs. 2 and 3 looking in a direction at right angles thereto.

Figs. 6, 7 and 8 are fragmentary sectional details showing respectively the position assumed during the feeding of the blank into the receiving recess of the operating arm, the position assumed prior to the insertion of the blank in the bottle body and the position assumed after the insertion of the blank in the bottle body.

Fig. 9 is a detailed view of the operating cam for operating the inserting mechanism.

Fig. 10 is an enlarged sectional detail through the spinning mechanism.

Fig. 11 is an enlarged elevation of the spinning mechanism.

Fig. 12 is an enlarged perspective detail of the spinning head, and

Fig. 13 is a further enlarged fragmentary section through a portion of the spinning head showing the bearing pins engaged by the portions of the bottle bottom to be spun.

In the drawings like letters of reference indicate corresponding parts in each figure.

1 indicates the body of the machine upon which is secured a bracket 2 carrying a standard 3 provided with a vertical slot 4, from which extends studs 5 and 6 adjacent its upper and lower ends, carrying friction rollers 7 and 8. 9 is a

bar which fits between the upper and lower pairs of friction rollers 7 and 8 to move vertically therebetween.

10 is a projecting arm extending rigidly from the bar 9 through the slot 4 of the standard 3. 11 is a rocking shaft mounted in bearings 12 and 13 carried by the body of the machine, the shaft 11 at one end being provided with a short arm 14 connected by a link 15 to the projecting arm 10 carried by the vertically movable bar member 9. 16 is a cam shaft to which is secured a cam member 17 having a cam groove 18 with which coacts the cam roller 19 carried by the vertical movable member 9.

20 is a flange plate carried by the bracket 2 extending in a vertical position and in which is located the orifices 21 and 22. 23 is a trough like receptacle secured at one end in the orifice 21, the inner end of the trough being provided with a circular portion 24 fitting the orifice 21 and extending flush with the outer face of the flange plate 20. 25 is a stationary rod extending from the flange plate 20 and on which is slidably mounted the hub 26 of a pressure plate 27 so as to slide longitudinally thereof. 28 is a pile of discs which are to be fed forward by the pressure of the plate 27 bearing against the rear end of the pile, such pressure being exerted by a weight 29 hung upon a cable 30 extending over guide pulleys 31 and 32.

33 is a long arm secured at the opposite end of the rocking shaft 11, the inner face of which slidably engages the outer face of the flange plate 20 and has formed therein a circular recess 34 corresponding in depth to the depth of each disc of the pile 28 and from which extends an orifice 35 through which the inserting plunger hereinafter described operates.

By the operation of the cam 17 imparting vertical movement to the bar 9, the shaft 11 is rocked so as to swing the arm 33 so that the recess 34 is alternately in a position concentric with the orifice 21 and the orifice 22 of the flange plate 20. When the recess 34 is opposite the orifice 21, the operation of the pressure plate 27 forces one of the discs of the pile 28 into the recess 34. The arm 33 is then swung downward carrying the recess 34 to a concentric position to the orifice 22. 36 indicates, mostly by dotted lines in Fig. 1, a turret holder carrying turrets 37 which are successively brought opposite to the orifice 22.

After one of the discs 28 has been inserted in the recess 34 and the arm 33 swung, the disc is carried opposite to the orifice 22 ready for insertion into the end of the bottle body 38 held in

a mandrel 37. 39 is a bearing member in which is held a pusher rod 40 which moves longitudinally therein and is provided, at its outer end, with a pusher head 41 which engages the disc 28 and forces it through the orifice 35 so as to upset the annular edge of the disc as indicated at 28^x forcing the disc into the body of the bottle so that the upset edges 28^x thereof engage the inner annular face of a bottle body.

10 42 is a cam secured to the shaft 16 and provided with a cam groove 43 into which the cam roller 44 extends, the cam roller 44 being carried by the pusher rod 40. It will, therefore, be seen that the cam 42 is so timed that when the disc 15 28 is brought opposite to the orifice 22 the pusher rod 40 and head 41 are forced forward to insert the disc in the bottle body as above described.

15 After the disc has been inserted in the bottle, the turret 36 is again rotated another step so 20 that the bottle body with its inserted disc is carried opposite to the spinning point and spun by mechanism which I will now describe.

20 45 is the main operating shaft of the spinning mechanism from which the shaft 16 is driven through suitable gearing indicated at 45^x. 25 46 is a base member supported upon the main body of the machine and carrying the stationary bearing member 47 carrying the spaced apart bearings 47^x and 47° in which is mounted the independently driven shaft 53. The upper portion of the bearing member 47 is formed into a longitudinal guideway 48 in which is slidably mounted an upper bearing member 49 carrying the spaced apart bearings 49^x and 49°. 50 is a short shaft journaled in the bearings 49^x and 49° and bearing at its inner end against a thrust bearing 51. 52 are lugs extending from the inner end of the bearing member 49.

50 54 are lugs extending from the stationary bearing member 47 in which is mounted a short shaft 55. 56 is an arm secured at one end on the shaft 55 and pivotally connected at its opposite end between the lugs 52 as indicated at 51. 58 is an arm also mounted upon the shaft 55 and provided at its free end with a cam roller 59 coacting with the cam 60 secured to the shaft 45. The arms 56 and 58 are adjustably connected together by means of the spaced apart lug members 61 and 62 forming part of the arm 58 and interposed 55 lug member 63 forming part of the arm 56.

55 64 and 65 are set screws extending through the lugs 61 and 62 so as to bear against opposite sides of the lug 63. By this means the arms 56 and 58 may be adjusted in relation to each other.

60 66 is a gear mounted upon the shaft 53 and feathered thereto so as to be adjustable longitudinally of the shaft between the bearings 47^x and 47°. 67 is a broad gear secured to the shaft 50 with which the gear 66 meshes. 69 is a spinner head provided with an annular groove 70, across which extend transverse roller pins 71 which are spring 65 pressed by a spring 72 held in bearing position against the end of the pin by means of the screw 73.

65 70 After the turret has been turned so as to carry the mandrel 37 from a position opposite the orifice 22 to a position opposite the spinning head 69, the cam 60 coacting with the arms 58 and 56 force the upper bearing member 49 together with the spinning head 69 against the rim of the bottle body and the opposite portion of the disc end so as to spin it inwardly, the head 69 revolving at a high rate of speed with the bottle rim in engagement with the roller pin 71 thereby reducing the 75 friction to a minimum.

From this description it will be seen that I have devised a very simple device by which the discs forming the bottle ends of a paper bottle are inserted in the body of the bottle and the rim of the bottle spun around so as to retain the inserted discs in position within the bottle body. 5

What I claim as my invention is:

1. In a paper bottle making machine, the combination with a movable carrier for the open ended bottle bodies, a paper disc holder, means 10 for feeding the discs to a position opposite the open end of the bottle, means for forcing the discs into the bottom end so as to fit within the bottle body, means for spinning the end edge of the bottle body and the upset portion of the disc 15 inward, such means comprising a suitably driven shaft mounted in a stationary bearing member, a longitudinally movable bearing member mounted upon the stationary bearing member, a shaft journaled in the movable bearing member, a 20 broad toothed gear secured to the shaft of the movable bearing member, a narrow toothed gear mounted upon a suitable driven shaft in mesh with the broad toothed gear, a spinning head secured to the longitudinally movable shaft, and 25 cam means for forcing the movable bearing member longitudinally against the open end of the bottle when brought to the spinning position.

2. In a paper bottle making machine, the combination with a movable carrier for the open 30 ended bottle bodies, a paper disc holder, means for feeding the discs to a position opposite the open end of the bottle, means for forcing the discs into the bottom end so as to fit within the bottle 35 body, means for spinning the end edge of the bottle body and the upset portion of the disc inward, such means comprising a suitably driven shaft mounted in a stationary bearing member, a longitudinally movable bearing member mounted 40 upon the stationary bearing member, a shaft journaled in the movable bearing member, a broad toothed gear secured to the shaft of the movable bearing member, a narrow toothed gear mounted upon a suitable driven shaft in mesh with the broad toothed gear, a spinning head secured to the longitudinally movable shaft, cam 45 means for forcing the movable bearing member longitudinally against the open end of the bottle when brought to the spinning position, and means for adjusting the throw of the movable 50 member.

3. In a paper bottle making machine, the combination with a movable carrier for the open ended bottle bodies, a paper disc holder, means 55 for feeding the discs to a position opposite the open end of the bottle, means for forcing the discs into the bottom end so as to fit within the bottle body, means for spinning the end edge of the bottle body and the upset portion of the disc inward, such means comprising a suitably driven 60 shaft mounted in a stationary bearing member, a longitudinally movable bearing member mounted upon the stationary bearing member, a shaft journaled in the movable bearing member, a broad toothed gear secured to the shaft of the 65 movable bearing member, a narrow toothed gear mounted upon a suitable driven shaft in mesh with the broad toothed gear, a spinning head secured to the longitudinally movable shaft, a shaft journaled in stationary brackets, an arm mounted upon the shaft at one end and pivotally connected to a movable bearing member at the opposite end, an arm also mounted upon the shaft provided with a cam roller at its free end, and 70 a suitably driven cam coacting with the roller. 75

4. In a paper bottle making machine, the combination with a movable carrier for the open ended bottle bodies, a paper disc holder, means for feeding the discs to a position opposite the open end of the bottle, means for forcing the discs into the bottom end so as to fit within the bottle body, means for spinning the end edge of the bottle body and the upset portion of the disc inward, such means comprising a suitably driven shaft mounted in a stationary bearing member, a longitudinally movable bearing member mounted upon the stationary bearing member, a shaft journalled in the movable bearing member, a broad toothed gear secured to the shaft of the movable bearing member, a narrow toothed gear mounted upon a suitable driven shaft in mesh with the broad toothed gear, a spinning head secured to the longitudinally movable shaft, a shaft journalled in stationary brackets, an arm mounted upon the shaft at one end and pivotally connected to a movable bearing member at the opposite end, an arm also mounted upon the shaft provided with a cam roller at its free end, and a suitably driven cam coacting with the roller, a pair of spaced apart lugs carried by the cam roller arm, a lug extending from the arm pivoted to the movable bearing member and extending between the aforesaid lugs, and set screws carried by the lugs of the roller cam arm and bearing against opposite sides of the interposed lug.
5. In a bottle bottom inserting mechanism for paper bottle making machines, a carrier for the discs forming the bottle bottoms, a rock shaft on which the disc carrier is mounted to swing to and from the bottle bottom inserting position, a main drive shaft, and means operated therefrom for rocking the shaft.
6. In a bottle bottom inserting mechanism for paper bottle making machines, a carrier for the discs forming the bottle bottoms, a rock shaft on which the disc carrier is mounted to swing to and from the bottle bottom inserting position, a crank arm secured to the shaft, a main driving shaft, a cam secured thereto, a bar guided to move longitudinally, a roller carried by the bar to coact with the cam, and a link connection between the bar and crank arm.
7. In a paper bottle making machine, a bearing member having opposed bearing portions and a slideway formed above such bearing portions, a drive shaft mounted in the bearing portions, a pinion mounted on the drive shaft between such portions, a slide in the slideway having opposing bearing portions, a spinner shaft mounted in the slide, a spinner head and a broad toothed gear mounted on the spinner shaft and held to move longitudinally with the slide when in mesh with the pinion of the drive shaft, and means for moving the spinner shaft and slide longitudinally.

ANDREW BODOR.
